UNITED STATES PATENT OFFICE.

PAUL BALKE AND GUSTAV LEYSIEFFER, OF TROISDORF, GERMANY.

RECORD FOR GRAMOPHONES AND THE LIKE.

No Drawing.

Application filed November 18, 1921. Serial No. 516,224.

To all whom it may concern:

Be it known that we, PAUL BALKE and GUSTAV LEYSIEFFER, residing at Troisdorf, Germany, have invented an Improvement 5 in Records for Gramophones and the like, of which the following is a specification, and for which application for Letters Patent has been made in the following countries on the dates set forth: Germany, Oct. 19, 10 1920; Denmark, Aug. 4, 1921; England, Sept. 23, 1921; Finland, Aug. 9, 1921; France, Aug. 10, 1921; Holland, Aug. 4, 1921; Italy, Aug. 3, 1921; Japan, Sept. 10, 1921; Luxemburg, Aug. 3, 1921; Norway, 15 Aug. 12, 1921; Austria, Aug. 1, 1921; Poland, Aug. 4, 1921; Portugal, Sept. 3, 1921; Roumania, Aug. 20, 1921; Sweden, Aug. 3, 1921; Switzerland, Aug. 3, 1921; Spain, Aug. 25, 1921; Hungary, Aug. 4, 1921; Belgium, 20 Sept. 23, 1921; Bohemia, Sept. 22, 1921.

The purpose of the invention is to provide a phonograph record of superior quality and durability which will nevertheless be very cheap in cost. In our British Patent No. 169,232 based on application 25 16,281 of 1920, we have described a material suitable for making a phonograph record and consisting of a homogeneous mass of cellulose derivative such as cellulose esters or cellulose ethers as, for example, ethylcel- 30 lulose, a greater quantity of a finely ground filling material, for example, cork or fibrous substances such as cellulose, cotton, peat and the like, and a gelatinizing agent such as methyl or ethyl-urea utilized in excess, 35 that is, in a larger proportion than is required for gelatinizing the cellulose derivative. As set forth in said patent the following ingredients are preferred:—

40 35 kg. nitro-cellulose, 42 kg. cellulose, 5 kg. any suitable black pigment for coloring the records, 18 kg. gelatinizing agent, such as methyl- or ethyl-urea.

In accordance with our present invention 45 we provide a body or core for the record consisting of a base of cheap material such as resins to which are added mineral or fibrous substances, thin metal sheets, prepared or unprepared cardboards, thin wood or similar substances. On this body there is formed 50 a superficial coating consisting of a thin layer of the material or composition above set forth and which receives the sound reproducing grooves of the completed record.

This material may be made of exceeding 55 thinness, for example, .3 of a millimeter, a thinness which would be impracticable in the case of shellacked material hitherto employed.

The coating material may be produced in 60 very thin sheets and used for covering the body of base material or it may be ground to a fine powder which may be sprayed on the body and then compressed thereon to form a single plate.

As the composition described is in itself 65 cheaper than the shellac compositions hitherto commonly used for records its employment in connection with a still cheaper body or core makes an exceedingly cheap 70 record. At the same time this relatively cheap coating material may be made still thinner than would be practicable in the case of shellac. This not only gives cheapness 75 but provide a record superior to one made of shellac because of the elasticity and flexibility of the material. The shellac material hitherto employed is brittle and in a thin layer would be likely to crack under relatively small shocks and strains and in a 80 thin layer would not form a groove accurately reproducing sound whereas the elastic material employed is not brittle but highly durable and will give accurate sound reproduction.

Having now particularly described and ascertained the nature of our said invention and in what manner the same is to be performed, we declare that what we claim is:—

1. A gramophone record comprising a 90 body of base material having a superficial coating receiving the sound groove and comprising a vehicle of gelatinized cellulose derivative and a fibrous filler.

2. A gramophone record comprising a 95 body of base material having a superficial coating receiving the sound groove and consisting of a compound comprising cellulose ester, a greater mass of finely ground filler and an excess of gelatinizing agent.

In testimony whereof we affix our signatures in presence of two witnesses.

DR. PAUL BALKE.
DR. LEYSIEFFER.

Witnesses:

ANTON NORM,
JOSEF STEINBERGER.
